EARTH BORING DEVICE

Arthur H. Graham, Dallas, Tex., assignor to
Socony-Vacuum Oil Company, Incorporated,
New York, N. Y., a corporation of New York

Application March 20, 1941, Serial No. 384,304

2 Claims. (Cl. 255—69)

This invention has to do with devices for boring holes into the earth and particularly with those devices for boring holes to relatively shallow depths through relatively soft and/or unconsolidated material, such as wells, holes for placing shots for geophysical prospecting for oil, holes for examining the flow of gases in the soil, for obtaining samples of the soil at variable depths below the surface, and the like.

The invention has for its object the provision of a boring device of auger type combined with a casing and a boring removing means.

The device is shown in the single figure of the drawing attached to this specification and comprises a central shaft 1, surrounded by a casing 2. This central shaft 1 is provided at this lower end with a cutting auger composed of lead screw 3, external cutting flight 4 and a removal flight 5. The lower end of the shaft and the auger are supported in the casing by a bearing 7 and a spider composed of several members 8, 8. The external cutting flight 4 is of a diameter at least equal to the external diameter of the casing 2, and the heel of this cutting flight 4 is of such a diameter at the point 9 that it contacts with and is supported by bearing 7. The external diameter of the flight 5 is such that it is prevented from radial movement by engaging with the spider members 8 which hold it centered within the casing. On shaft 1 upwardly of flight 5 there are conveyor flights 10 for the purpose of moving borings upwardly. These flights 10 are preferably of a pitch different from that of flights 5, and may be either sectional and spaced

at intervals along shaft 1, as shown, or continuous.

I claim:

1. A boring head for earth boring implements comprising a casing, in said casing a shaft, an auger mounted upon the lower end of said shaft having a cutting flight extending axially beyond said casing and having a diameter at least as great as the external diameter of said casing, rearward flights of said auger within said casing being of less diameter than the internal diameter of said casing and bearing means internal of said casing adjacent its end to cooperate with the peripheral edge of said rearward flights to hold the shaft and auger centered in said casing, and conveyor flights greater in diameter than said rearward flights and having a pitch different from the rearward flights to facilitate removal of cuttings produced by the rotation of the auger.

2. A boring head for earth boring implements comprising a casing, in said casing a shaft, an auger mounted upon the lower end of said shaft having a cutting flight extending axially beyond said casing and having a diameter at least as great as the external diameter of said casing, rearward flights of said auger within said casing being of less diameter than the internal diameter of said casing and bearing means internal of said casing adjacent its end to cooperate with the peripheral edge of said rearward flights to hold the shaft and auger centered in said casing, and conveyor flights greater in diameter than said rearward flights to facilitate removal of cuttings produced by the rotation of the auger.

ARTHUR H. GRAHAM.
